UNITED STATES PATENT OFFICE

GEORGE S. HENSEL, OF PHILADELPHIA, PENNSYLVANIA, ASSIGNOR TO THE HENSEL, COLLADAY COMPANY, OF PENNSYLVANIA.

DESIGN FOR A SKIRT AND SHOE PROTECTOR.

SPECIFICATION forming part of Design No. 30,747, dated May 9, 1899.

Application filed April 11, 1899. Serial No. 712,673. Term of patent 14 years.

To all whom it may concern:

Be it known that I, GEORGE S. HENSEL, a citizen of the United States, residing in the city and county of Philadelphia, State of Pennsylvania, have invented and produced a new and original Design for a Combined Skirt and Shoe Protector, of which the following is a specification, reference being had to the accompanying drawings, forming part thereof.

5 The leading features of my design for a combined skirt and shoe protector are, first, a representation of fluffy bulbs on the side or face of the head thereof, and, next, a head having the representation of fluffy bulbs on the side 5 or face of the same and a brush pendent from the lower edge thereof.

Figure 1 represents a side elevation of a piece of a combined skirt and shoe protector

embodying my design. Fig. 2 represents a section thereof on line $x x$, Fig. 1.

In the drawings, A designates a head, and B a design brush pendent from the lower edge thereof.

C designates fluffy bulbs on the side or face of said head, the same extending in the longitudinal direction thereof.

Having thus described my invention, what I claim as new, and desire to secure by Letters Patent, is—

The design for a combined skirt and shoe 30 protector substantially as shown and described.

GEORGE S. HENSEL.
